CLAIM

The ornamental design for a light with housing, as shown and described.

DESCRIPTION

FIG. 1 is a perspective view of a light with housing showing the new design.

FIG. 2 is a side view of the light with housing of FIG. 1, with all other sides being identical.

FIG. 3 is a top view of the light with housing of FIG. 1.

FIG. 4 is a bottom view of the light with housing of FIG. 1.

FIG. 5 is a perspective view of the light with housing of FIG. 1, shown in an alternate configuration.

FIG. 6 is a side view of the light with housing of FIG. 1, shown in the alternate configuration, with all other sides being identical.

FIG. 7 is a top view of the light with housing of FIG. 1, shown in the alternate configuration; and,

FIG. 8 is a bottom view of the light with housing of FIG. 1, shown in the alternate configuration.

The dotted lines in the drawings depict portions of the light with housing that forms no part of the claimed design.
